UNITED STATES PATENT OFFICE

152,881

DESIGN FOR A PORTABLE WHEEL BALANCING DEVICE

Lee Hunter, Jr., University City, Mo.

Application December 3, 1947, Serial No. 142,938

Term of patent 14 years

(Cl. D14—3)

To all whom it may concern:

Be it known that I, Lee Hunter, Jr., a citizen of the United States and a resident of University City, in the county of St. Louis and State of Missouri, have invented a new, original, and ornamental Design for Portable Wheel Balancing Device, of which the following is a specification, reference being had to the accompanying drawing, forming part thereof.

Fig. 1 is a perspective view of a portable wheel balancing device, showing my new design,

Fig. 2 is a front end elevational view,

Fig. 3 is a top plan view,

Fig. 4 is a side elevational view looking at the

side opposite from the side shown in Fig. 1; and Fig. 5 is a rear end elevational view.

I claim:

The ornamental design for a portable wheel balancing device, substantially as shown.

LEE HUNTER, JR.
